UNITED STATES PATENT OFFICE

WILLIAM T. BARRATT, OF BENNINGTON, VERMONT, ASSIGNOR TO CHARLES COOPER COMPANY, OF BENNINGTON, VERMONT, A PARTNERSHIP OF ELIZABETH COOPER KELLEY AND CHARLES C. KELLY

ADJUSTABLE BOBBIN SUPPORT

Application filed September 24, 1928. Serial No. 307,911.

This invention relates to an adjustable bobbin support for knitting machines.

In providing bobbin supports for knitting machines it has been the custom to permanently attach the same to the frame of the machine at such a location thereon that any of the regular stock sizes of bobbins may be employed without regard to the distance that may intervene between the tip of the bobbin and the nearest thread guide. It has been determined, however, that there should be a definite distance between the thread guide and the tip of the bobbin in order that the thread shall unwind easily and without slanting, and as there is considerable variation in the height of the bobbins it is evident that after the bobbin support is positioned to allow a certain size of bobbin to unwind satisfactorily, that if the bobbin is changed and the distance between the thread guide and the tip of the bobbin is either increased or diminished that the thread will not unwind in the efficient manner that is desired.

The object of this invention is to provide a bobbin support that may be adjusted upon the knitting machine in such a manner that no matter what the height is of the bobbins that are employed the distance from the tip of the bobbin to the first thread guide, which is always located directly thereabove, will be approximately the same.

The invention consists in an adjustable bobbin support for knitting machines as set forth in the following specification and particularly as pointed out in the claims thereof.

Referring to the drawings:

Figure 1 represents a front elevation of the lower portion of a knitting machine, a bobbin support embodying my invention being mounted thereon.

Fig. 2 is a vertical section taken on the line 2-2 of Fig. 1, looking in the direction of the arrows on said line.

Fig. 3 is a detail sectional view illustrating the means for clamping the bobbin frames to the guide members.

In the drawings, 5 represents the main frame of a knitting machine and 6 are vertical guide members which are rigidly secured in any suitable manner to the inner sur-

face of the side members of said frame. Mounted upon each of the guide members 6 is a bobbin frame 7 having a groove 8 formed therein, in which the guide member 6 is located and by means of which the frame 55 7 is guided upon said guide member. Each frame 7 is secured to its guide member 6 after being positioned thereon by means of a clamp member 9. Rods 10 are mounted at their opposite ends in each of the bobbin frames 7, 60 and adjustably mounted upon each of said rods are a plurality of trays 11 constituting supports for bobbins A. The upper surfaces of each of the trays 11 are recessed at 12 to receive the lower end of the bobbin, and a spindle 13 is provided upon each of the supports 11 in order that the bobbins A may be positioned centrally upon the support.

Located directly above each row of bobbins is a thread guide 14 having suitable eyes 15 70 therein through which the thread *a* from the bobbin is threaded. The eyes 15 are located directly above the bobbin in longitudinal alignment to the median line thereof. The thread guides 14 are secured to the frame 5 75 of the knitting machine by means of brackets 16.

In utilizing the bobbin support of this invention the bobbin frames 7 are positioned upon their respective guide members 6 so that 80 the tips of the bobbins A will be located at a position at which the thread *a* will unwind in its most efficient manner, it being understood that as the thread unwinds the tendency is for it to slide off and pull from the tip of 85 the bobbin as illustrated in the drawings.

It will furthermore be understood that the bobbins employed at any one time in connection with this device shall all be the same height and when it is desired to change from 90 one height or type of bobbin to a bobbin of a different height and type, the bobbin frames 7 are adjusted upon the guides 6 so that the tips of the new bobbins will be positioned to allow the thread to unwind therefrom in its 95 most efficient manner.

I claim:

1. A support for bobbins having, in combination, a pair of guide members, a bobbin frame slidably mounted upon each of said 100

guide members, means to clamp said frames to said members, rods mounted upon said frames and supports for bobbins upon said rods.

5 2. A support for bobbins having, in combination, a pair of guide members, a bobbin frame slidably mounted upon each of said guide members and provided with a groove therein by which said frame is guided upon said member, means to clamp said frame on said members, rods mounted upon said frame and supports for bobbins adjustably mounted upon said rods.

10 3. The combination with the frame of knitting machine of a pair of guide members fast thereto, a bobbin frame slidably mounted upon each of said members, means to clamp said bobbin frames at different elevations upon said guide members, rods mounted upon 15 said bobbin frames and supports for bobbins adjustably mounted upon said rods.

20 In testimony whereof I have hereunto set my hand.

WILLIAM T. BARRATT.
